(57) CLAIM

The ornamental design of a front housing for a compressor, as described in the foregoing specification and the accompanying figures.

DESCRIPTION

FIG. 1 is a front view of a first embodiment of a front housing for a compressor.

FIG. 2 is a top view of this first embodiment of the front housing for a compressor.

FIG. 3 is a right side view of this first embodiment of the front housing for a compressor.

FIG. 4 is a left side view of this first embodiment of the front housing for a compressor.

FIG. 5 is a rear view of this first embodiment of the front housing for a compressor.

FIG. 6 is a bottom view of this first embodiment of the front housing for a compressor.

FIG. 7 is a perspective view of this first embodiment of the front housing for a compressor.

FIG. 8 is a cross-sectional view of this first embodiment of the front housing for a compressor, showing the shape of this embodiment of the design, along line 8—8 of FIG. 2.

FIG. 9 is a side view of compressor including this first embodiment of the front housing.

FIG. 10 is a front view of a front housing for a compressor showing a second embodiment of my new design;

FIG. 11 is a top view of FIG. 10,

FIG. 12 is right side view of FIG. 10;

FIG. 13 is a left side view of FIG. 10;

FIG. 14 is a rear view of FIG. 10;

FIG. 15 is a bottom view of FIG. 10;

FIG. 16 is a perspective view of FIG. 10;

FIG. 17 is a cross-sectional view of FIG. 10 taken along the lines 17—17 of FIG. 11; and,

FIG. 18 is a side view of FIG. 10.

It being understood that the broken lines are for illustrative purposes only.
